UNITED STATES PATENT OFFICE.

FRANK L. PUTNAM AND GEORGE EBERSPACHER, OF HOUSTON, TEXAS; SAID
EBERSPACHER ASSIGNOR TO SAID PUTNAM.

AUTOMATIC GAS VALVE.

1,409,466.

Specification of Letters Patent. Patented Mar. 14, 1922.

Application filed November 20, 1920. Serial No. 425,558.

To all whom it may concern:

Be it known that we, FRANK L. PUTNAM and GEORGE EBERSPACHER, citizens of the United States, residing at Houston, in the 5 county of Harris and State of Texas, have invented certain new and useful Improvements in Automatic Gas Valves, of which the following is a specification.

This invention relates to new and useful 10 improvements in a combination gas and water valve.

One object of the invention is to provide a device of the character described which is specially adapted for use in connection 15 with gas water heaters for controlling the supply of gas to the burner and embodies a novel combination whereby gas will be automatically admitted to the burner when the water is turned on to be admitted to the 20 water coil of the heater.

Another object of the invention is to provide a valve that will automatically shut off the gas when the water is turned off.

A further feature of the invention em- 25 bodies a novel construction which is not liable to become disabled or to get out of order by reason of the fact that the working parts are protected by suitable surrounding protecting casings.

With the above and other objects in view 30 the invention has particular relation to cer- tain novel features of construction, opera- tion and arrangement of parts, an example of which is given in this specification and 35 illustrated in the accompanying drawings, wherein:—

The figure shows a vertical sectional view of the device.

Referring now more particularly to the 40 drawing, the numeral 1 designates the water valve casing which is cup-like in form, and anchored to the bottom thereof there is the upstanding sleeve 2 which is spaced from the walls of the casing. Fitted over this sleeve 45 there is a valve 3 of the form of an inverted cup and provided with an outlet opening 4. The casing 1 is secured to the upper end of a yoke 5 and to the lower end of said yoke there is secured a tubular gas-valve casing 50 6 provided with the inlet opening 7 through which gas enters from the gas inlet pipe 8. A valve rod 9 works through suitable stuff- ing boxes 10 and 11 provided in the lower and upper ends, respectively, of the casings 55 1 and 6. The upper end of this rod is at-

tached to the valve 3 and to the lower end thereof the valve 12 is secured. Within the casing 6 there is a strong coil spring 13 which surrounds the rod 9 and is interposed between the valve 12 and the opposite end 60 of the casing 6. Water is admitted through the water inlet 14 and when the water is turned on it enters within the sleeve 2 and lifts the valve 3 until the opening 4 clears the upper end of said sleeve and the water 65 then passes through the pipe 15 to the coil 16. At the same time the valve 12 is automatically lifted, permitting gas to pass out through the port 19, controlled thereby, in the bottom of the casing 6 and the gas 70 then passes to the burner 17 through the pipe 18. The gas from the burner is ignited by the usual pilot light, (not shown).

It is obvious from the foregoing that when the water is turned on the pressure thereof 75 will automatically open the gas valve and admit gas to the burner 1 arranged underneath the water coil and whereby said coil will be heated and when the water is turned off the spring 13 will cut off the supply of 80 gas and thus extinguish the flame.

It is to be noted from the description and drawings that the operating parts of the mechanism are completely enclosed within 85 protecting casings and should said casings become dented or otherwise injured it will not affect the operation of the valve.

What we claim is:—

1. A device of the character described, in- 90 cluding a water valve casing and a gas valve casing, the former of which has a water inlet and the latter of which has a gas outlet port, a sleeve having a uniform exterior within the water valve casing and spaced from the wall thereof, within which the water is delivered through said water inlet, 95 a valve fitted over said sleeve and at all positions forming a water tight joint therewith, and provided with an outlet port, a valve normally closing said gas outlet port, a stem connecting said valves and a single yieldable member within the gas valve cas- 100 ing normally holding both valves closed.

2. A device of the character described, in- 105 cluding a pair of valve casings, a cylindrical upstanding sleeve anchored to the bottom of one casing and spaced from the wall thereof, an inverted cup-shaped valve fitted over said sleeve and forming, at all times, a tight joint therewith and provided with a side port 110

which is opened by the sleeve when the valve is elevated and closed thereby when the valve is lowered, an inlet through said casing into the interior of the sleeve, an outlet leading from said casing, the other casing being provided with an outlet port, a disc valve normally closing said outlet port, a rigid valve stem to the respective ends of which said respective valves are attached, a resilient member within the last mentioned casing normally holding the valves in closed posi-

tion, and a gas inlet entering said last mentioned casing.

In testimony whereof we have signed our names to this specification in the presence of two subscribing witnesses.

FRANK L. PUTNAM.
GEORGE EBERSPACHER.
